AUTOMATIC RECORD CHANGING APPARATUS

Jerald D. Weaver, Fort Wayne, Ind., assignor to
Farnsworth Television and Radio Corporation,
a corporation of Delaware

Application December 6, 1941, Serial No. 421,891

12 Claims. (Cl. 274—10)

This invention relates to an automatic phonograph and particularly to a mechanism for moving and reversing records of different diameters.

The object of the present invention is to provide an improved automatic phonograph in which both sides of a stack of intermixed records supported on the turntable may be played and thereafter removed from the turntable.

Another object of the invention is to provide improved mechanism for moving a played record from a turntable, reversing it, and moving the reversed record back to the turntable.

Another object of the invention is to provide improved mechanism for moving a played record from a turntable to a record magazine.

Another object of the invention is to provide improved record-engaging means which is adapted to be adjusted to engage the top record on the turntable.

Another object of the invention is to provide improved record-engaging means which is adapted to engage records of different sizes.

Another object of the invention is to provide improved pickup arm control mechanism for accurately positioning a pickup arm over the initial playing grooves of records of different sizes.

In accordance with the present invention, there is provided an automatic phonograph which has a rotatable turntable and record-reversing mechanism. The record-reversing mechanism comprises a record-moving mechanism mounted beyond the periphery of the turntable for moving to a record-reversing position, record-reversing means connected to said record-moving means for moving therewith and for moving relative thereto when the record-moving means is in record-reversing position for reversing a record and a pair of arms connected to the record-reversing means for moving relative thereto into engagement with a record on the turntable and for moving therewith to the record-reversing position. After a record on the turntable is played, the record-moving means, the record-reversing means and the arms are actuated for respectively moving the arms into engagement with the record on the turntable, moving the record on the turntable to record-reversing position, reversing the moved record, returning the reversed record to the turntable and pivoting the arms out of engagement with the reversed record.

In accordance with another feature of the invention there is provided an automatic phonograph which has a rotatable turntable for sup-

porting a stack of records, a record magazine and record-moving mechanism. The record-moving mechanism comprises means for moving the turntable vertically relative to its axis for maintaining the top record on the turntable at a predetermined elevation, record-moving means mounted beyond the periphery of the turntable for moving to a record-discard position, a pair of arms connected to the record-moving means for moving relative thereto into engagement with the top record on the turntable and for moving with the record-moving means to the record-discard position, a rotatable member on the record-moving means and operatively associated with the arms for cooperating in moving the arms into and out of engagement with the record on the turntable, and actuating means on the record magazine for moving the rotatable member as the record-moving means is moved to the record-discard position. Normally the arms are in a position beyond the periphery of the top record on the turntable and at the predetermined elevation of the top record. When the top record on the turntable is played, the turntable-moving means, the record-moving means, and the rotatable member are actuated for respectively moving the arms into engagement with the top record on the turntable, moving the top record from the turntable to the record-discard position, depositing the moved record into the record magazine, moving the turntable to move the top record thereon to the predetermined elevation and returning the arms to the normal position.

In accordance with another feature of the invention, there is provided an automatic phonograph which has a rotatable turntable for supporting a stack of records, a record magazine and record-changing mechanism. The record-changing mechanism comprises means for moving the turntable vertically relative to its axis for maintaining the top record thereon at a predetermined elevation, record-moving means mounted beyond the periphery of the turntable for moving to record-reversing and record-discard positions, record-reversing means connected to the record-moving means for moving therewith and for moving relative to the record-moving means when the record-moving means is in the record-reversing position for reversing a record, a pair of arms connected to the record-reversing means for moving relative thereto into engagement with the top record on the turntable and for moving with the record-reversing means to the record-reversing and record-dis-

carding positions, a rotatable member operatively associated with the arms for cooperating in moving said arms into and out of engagement with the top record on the turntable and being associated with the record-reversing means for moving therewith, and actuating means on the magazine for moving the rotatable member as the record-moving means is moved to the record-discarding position. Normally the arms are in a position beyond the periphery of the top record on the turntable and at the predetermined elevation of the top record. After one side of the top record on the turntable is played, the record-moving means, the record-reversing means and the rotatable member are actuated for respectively moving the arms into engagement with the top record on the turntable, moving the top record from the turntable to the record-reversing position, reversing the record, returning the reversed record to the turntable and moving the arms out of engagement with the reversed record. After the reversed record is played, the turntable-moving means, record-moving means, and the rotatable member are actuated for respectively moving the arms into engagement with the reversed record, moving the reversed record to record-discarding position, depositing the reversed record into the magazine, moving the turntable to move the top record thereon to the predetermined elevation, and returning the arms to the normal position.

In accordance with another feature of the invention, there is provided an automatic phonograph which has a rotatable turntable for supporting a record thereon and record-gripping mechanism. The record-gripping mechanism comprises a pair of arms movably mounted beyond the periphery of the turntable for moving into engagement with opposite peripheral edge portions of the record on the turntable, and means including a rotatable member operatively associated with the arms for moving the arms.

In accordance with another feature of the invention, there is provided an automatic phonograph which has a rotatable turntable for supporting a record thereon, a pickup arm and a controlling mechanism for the pickup arm. The controlling mechanism comprises means for elevating the pickup arm above the record on the turntable and lowering it into engagement therewith, means for moving the pickup arm outwardly beyond the periphery of the record on the turntable and returning it toward the center of the turntable, a lever movably connected to the pickup arm and adapted to be moved by the pickup arm elevating means relative to the pickup arm in a plane parallel to the axis of the turntable, and a projection on the lever for engaging the peripheral wall of the record on the turntable for stopping the return movement of the pickup arm. The projection is adapted to move out of engagement with the peripheral wall of the record on the turntable when the pickup arm is moved into engagement with it.

For a better understanding of the invention, together with other and further objects thereof, reference is made to the following description taken in connection with the accompanying drawings, and its scope and its steps will be pointed out in the appended claims.

In the accompanying drawings:

Fig. 1 is a top plan view of the record-changing apparatus in accordance with the invention showing a turntable with intermixed records

thereon, a magazine and mechanism for reversing and discarding records;

Fig. 2 is a side elevation showing the mechanism for raising and lowering the turntable;

Fig. 3 is a side elevation of the upper portion of the record-changing apparatus showing a stack of intermixed records on the turntable, a magazine for receiving played records, and the record-moving mechanism in two positions;

Fig. 4 is an end view with parts broken away showing a part of the mechanism for actuating the record-gripping arms;

Fig. 5 is a view of the driving mechanism for rotating the record-reversing means;

Fig. 6 is a fragmentary view showing the mechanism for moving the record-gripping arms into engagement with the top record on the turntable;

Fig. 7 is a fragmentary view showing the mechanism for moving and positioning the pickup arm;

Fig. 8 is a fragmentary view showing a section taken through the record-engaging portion of one of the record-gripping arms;

Fig. 9 is a top view of a portion of the turntable-moving mechanism shown in Fig. 2;

Fig. 10 shows a control dial for predetermining the elevation of the turntable;

Fig. 11 is a fragmentary view taken on line 11—11, Fig. 2, showing the relationship between the cam track switching member and the cam wheel to which it is connected.

Referring now particularly to Figs. 1 and 2 of the drawings, the invention here illustrated shows a record-changing apparatus which includes a base plate 14 with a well 15 formed therein. A supporting bracket 16 is suitably affixed to the underside of the base plate 14 and is adapted to support a tubular bearing element 17. The upper end of the bearing element 17 is provided with a flanged portion which in turn is provided with a groove or race for guiding a plurality of ball bearings 18 as shown in Fig. 2. The ball bearings 18 are adapted to rotatably support a flanged tubular shaft 19 by engaging the bottom of the flanged portion thereof. The tubular portion of the shaft 19 extends downwardly into the tubular bearing element 17. A turntable 20 is fixed to the flanged portion of the shaft 19 to rotate therewith as shown in Fig. 2. A stack of records 21 (Fig. 3) may be supported on the turntable 20 and the records are maintained in a centered position by a centering pin 22 rotatable with the turntable 20. The centering pin 22 extends upwardly above the turntable 20 and the top record on the turntable and downwardly through the tubular portions of both the shaft 19 and the element 17. The centering pin 22 is provided with a groove 23 which is engaged by a key member 24 provided on the interior of the tubular portion of the shaft 19. By this connection between the pin 22 and the shaft 19, the pin 22 is adapted to rotate with the shaft 19 but cannot move with it in a vertical plane. The turntable 20 may be rotated by connecting a suitable driving mechanism to the pin 22 for example, in the manner shown in U. S. Patent No. 2,012,185.

In the apparatus being described all of the records to be played are placed upon the turntable 20, as illustrated in Fig. 3. As each record is reproduced, it is removed from the turntable in a manner to be described hereafter. Each time a record is removed from the turntable, the turntable is automatically elevated the distance cor-

responding to the thickness of one record in order to maintain the top record on the turntable at a predetermined elevation relative to the record-moving mechanism.

Turntable-moving mechanism

The mechanism for elevating the turntable 20 is best illustrated in Figs. 2 and 9 and includes the bearing element 17 which supports the shaft 19 and the turntable 20. At the lower end of the element 17 there is provided a toothed portion 25 which is adapted to be engaged and moved by a toothed portion 26A of a member 26. The member 26 is pivotally supported intermediate its ends on a pin 27 which is fixed to the bracket 16. The right-hand end of the member 26 (Fig. 2) has a toothed portion 26B which is adapted to engage a small pinion gear 28 and to be driven thereby. The gear 28 is fixed to a shaft 29 which is rotatably mounted in the bracket 16. The shaft 29 also has affixed thereto a gear 30 and a ratchet wheel 31. The ratchet wheel 31 has associated therewith a pair of spring-biased pawls 32-32 which are pivotally connected to a plate 33. The plate 33 is fixed to the bracket 16 in a suitable manner as shown in Figs. 2 and 9. When the pawls 32-32 are in the position shown in Fig. 2, they prevent the rotation of the ratchet wheel 31 in a clockwise direction (Fig. 2) but do not prevent the rotation of the ratchet wheel 31 in the opposite direction.

The gear 30 serves to transmit counter-clockwise motion (Fig. 2) to the shaft 28 by means of a set of spring-biased levers 34 and 35 and the record-moving mechanism to be described hereafter. The lever 35 is connected at one end thereof to the bracket 16 to pivot relative thereto. A spring 36, one end of which is connected to the bracket 16 and the other end of which is in engagement with the lever 35, maintains the lever 35 in engagement with a stop 37 formed on the bracket 16 as shown in Fig. 2. One end of the lever 34 is pivotally connected to the free end of the lever 35. The end of the lever 34 which is connected to the lever 35 is maintained against an ear 35A formed on the lever 35 by a spring 38. As is shown in Fig. 2, one end of the spring 38 is connected to the lever 34 and the other end is connected to the lever 35. The free end of the lever 34 is shaped so that when it is in the position shown in Fig. 2 and is moved to the left (Fig. 2) it will engage one of the teeth on the periphery of the gear 30 to transmit motion thereto.

As will be described hereafter, during the record-discarding operation, the record-moving mechanism, which will be described hereafter, is adapted to move the lever 35 in a counterclockwise direction (Fig. 2) against the tension of the spring 36. This counterclockwise movement of the lever 35 is sufficient to permit the lever 34 to move the gear 30 in a counterclockwise direction (Fig. 2) the distance between two adjacent teeth on the periphery of the gear 30. The counterclockwise movement of the gear 30 moves the shaft 29 and therewith the ratchet wheel 31 and the gear 28 a corresponding distance. After the shaft 29 is moved by the lever 34, it is maintained in its new position by the pawls 32-32. The movement of the gear 28 with the shaft 29 in a counterclockwise direction moves the member 26 in a clockwise direction (Fig. 2) sufficiently to raise the bearing element 17 the distance which corresponds to the thickness of one record. This movement of the bearing element

17 in turn raises the turntable 20 a corresponding distance.

After the turntable 20 is raised to its uppermost position, it is necessary to lower it before the apparatus is ready to play another stack of records. To lower the turntable 20, the pawls 32-32 must be moved out of engagement with the ratchet wheel 31 and the shaft 29 must be rotated in a clockwise direction (Fig. 2). This is accomplished by mechanism illustrated in Figs. 9 and 10 which includes a spring-biased member 39 one end of which is fixed in a suitable manner to an indicator head 40 to rotate therewith. The indicator head is provided with a suitable pointer which moves over a dial 41 shown in Fig. 10. The other end of the member 39 has formed thereon a flange 42 provided with lugs 42A and 42B-42B. The member 39 is mounted on the shaft 29 to move relative thereto and is held in the position illustrated in Fig. 9 by a spring 43 which is associated with the member 39 and the shaft 29 in a suitable manner, for example, such as that shown in Fig. 9. When the indicator head 40 is pushed to compress the spring 43, it forces the member 39 to move along the shaft 29 until the lug 42A is in engagement with a notch 44 formed in a hub 45 of the ratchet wheel 31. The movement of the member 39 against the biasing action of the spring 43 also moves the lugs 42B-42B into engagement with the ears 32A-32A formed on pawls 32-32 to move the pawls out of engagement with the ratchet wheel 31. Thereafter the shaft 29 may be moved in a clockwise direction (Figs. 2 and 9) by a corresponding movement of the indicator head 40. The clockwise movement (Fig. 9) of the shaft 29 moves the member 26 in a counterclockwise direction (Fig. 2) to lower the turntable 20. The turntable 20 may be lowered any desired distance depending upon the number of records which the operator wishes to play. The distance that the turntable 20 is lowered depends upon the distance that the indicator head 40 is moved in a clockwise direction (Fig. 10) relative to the dial 41. For example, if, after the turntable 20 has reached its uppermost position, the operator thereafter wishes to play three records on the turntable, the turntable is lowered a distance corresponding to the thickness of three records by moving the pointer on the indicator head 40 in a clockwise direction (Fig. 10) to number three on the dial 41. In this manner the turntable 20 is lowered far enough so that during the operation of the apparatus for reproducing the three records, the top record on the turntable is at a constant predetermined elevation relative to the record-moving mechanism to be described hereafter.

The entire apparatus may be stopped automatically after the bottom record on the turntable is reproduced by connecting to the shaft 29 a play control mechanism such as that disclosed in U. S. Patent No. 1,872,706.

Pickup arm mounting and mechanism for moving the pickup arm

The mounting of a pickup arm and the mechanism for moving a pickup arm is illustrated in Figs. 1, 6 and 7. A pickup arm 46 is mounted on a pedestal 47 which is fixed to the base plate 14 at one side of the turntable as shown in Figs. 1 and 7. The pickup arm 46 is mounted in such a manner that it may be moved in horizontal and vertical planes. At the free end of the pickup arm 46 there is provided a reproducer or a

pickup 48 with a stylus 49 which is adapted to cooperate with a record on the turntable as shown in Fig. 3 to reproduce the record. Intermediate the ends of the pickup arm 46 there is pivotally connected thereto a lever 50 in a suitable manner such as that shown in Fig. 7. To one end of the lever 50 there is affixed a downwardly extending pin 51. A spring 52 is connected to the lever 50 in the manner shown in Fig. 7 to maintain the lever 50 in the full-line position shown in that figure. As will be evident from the description hereafter, when the raised pickup arm 46 is moved from its outermost position shown in Fig. 1 toward the turntable 20 and the uppermost record on the turntable is a 12-inch record, the pin 51 will extend in the plane of the 12-inch record on the turntable and serve to position the stylus 49 of the pickup arm 46 over the initial playing groove of that record. As the pickup arm is lowered into engagement with the initial playing groove, the pin 51 is raised out of engagement with the top record on the turntable to permit the pickup arm to move toward the center of the turntable as the stylus 49 is tracking the playing grooves of the top record.

The end of the pickup arm 46 that rests on the pedestal 47 has connected thereto a tubular shaft 53 which extends downwardly through the pedestal 47 and below the base plate 14. A lever 54 is keyed to the lower end of the shaft 53 in such a manner that the lever 54 will move with the shaft 53 in a horizontal plane and is adapted to move a predetermined distance relative to the shaft 53 in a vertical plane. Fig. 7 shows one way of connecting the lever 54 and the shaft 53 to achieve these functions. The free end of the lever 54 has affixed thereto a downwardly extending pin 55 which is adapted to be engaged by a cam surface 56 on a cam wheel 57 for imparting horizontal movement to the lever 54. The cam wheel 57 is fixed to a shaft 58 which is rotatably mounted in a suitable bracket 59 fixed to the bottom of the base plate 14. The shaft 58 may be driven by any suitable motor and gear mechanism known in the art. U. S. Patent No. 2,012,185 discloses one form of such mechanism. The opposite end of the lever 54 is of tubular construction and is keyed to the shaft 53 as previously described. The upper end of the tubular portion of the lever 54 has affixed thereto an ear 60. A lever 61 is connected to the shaft 53 above the tubular portion of the lever 54 in a suitable manner so that the lever 61 may be moved in a horizontal plane relative to the shaft 53. The end of the lever 61 which is connected to the shaft 53 is of tubular construction and the lower end thereof is notched at 62 in such a manner that the ear 60 may come into engagement therewith for rotating with the lever 61 in a horizontal plane. While the lever 54 is moved in a counterclockwise direction from the position shown in Fig. 6, it moves therewith the lever 61 in the same direction. This movement of the lever 61 serves to actuate record-gripping arms and to create tension in a spring element which will be described hereafter.

A pin 63 extends through the tubular shaft 53. When the pin 63 is raised from the position shown in Fig. 7, its upper end engages one end of the lever 50 and pivots it in a counterclockwise direction (Fig. 7) against the tension of the spring 52. After the lever 50 engages the under side of the pickup arm 46, the movement of the pin 63 raises the pickup arm 46.

Near the lower end of the pin 63 there is provided a collar or flanged portion 63A which is adapted to frictionally engage the bottom of the tubular portion of the lever 54 when the pin 63 is raised and moves the lever 54 in a vertical plane relative to the shaft 53. This permits the ear 60 to engage and move the lever 61 when the lever 54 is moved in a horizontal plane. The bottom of the pin 63 rests on a lever 64 one end of which is pivotally connected to a bracket 65 by a pin 66. The bracket 65 is fixed to the bottom of the base plate 14 in a manner illustrated in Fig. 7. The opposite end of the lever 64 supports a roller 67 which is adapted to rest on a peripheral wall 68 of the cam wheel 57.

When a record on the turntable 20 is being reproduced, the cam wheel 57 remains stationary in the position shown in Fig. 7. When the pickup arm 46 reaches the tripping groove of a record being reproduced, a suitable tripping mechanism not shown initiates the rotation of the shaft 58 through one revolution. The tripping mechanism disclosed in U. S. Patent 2,018,881 may be incorporated in this apparatus to initiate the rotation of the shaft 58.

The first operation which the cam wheel 57 performs during its cycle of rotation is to elevate the stylus 49 of the pickup arm 46 out of engagement with a record being reproduced. This is brought about by the cam surface 56A moving into engagement with the roller 67 and raising the lever 64 and therewith the pin 63. When the pin 63 is raised, it pivots the lever 50 and raises the pickup arm 46 and therewith the stylus 49 out of engagement with the record on the turntable. After the stylus 49 of the pickup arm 46 is raised out of engagement with a record on the turntable 20, the roller 67 is in engagement with the surface 68. While the roller 67 is in engagement with the surface 68, the pickup arm 46 is maintained in its raised position. Thereafter, the portion 56C of the cam surface 56 engages the pin 55 and moves it, and therewith the lever 54, in a counterclockwise direction (Fig. 6). When the lever 54 is thus moved after the pin 63 is in its raised position, the ear 60 is in position to move the lever 61 in a corresponding direction. The counterclockwise movement of the lever 54 swings the tubular shaft 53 and therewith the pickup arm 46 in a counterclockwise direction (Fig. 1). While the pickup arm is being swung to its outermost position, the counterclockwise movement of the lever 61 creates tension in a spring and actuates record-gripping arms as has been previously stated and which will be described hereafter. After the cam surface 56C moves out of engagement with the pin 55, the pin 55 is maintained in an outermost position by the cam surface 56. When the inclined portion 56A of the cam surface 56 moves into the path of the pin 55, the levers 54 and 61 are permitted to be moved in a clockwise direction (Fig. 6) by means of spring tension developed while these levers are moved in a counterclockwise direction (Fig. 6). The ear 60 and the notch 62 are so arranged that the lever 54 will be moved in a clockwise direction (Fig. 6) against the friction between it and the collar 63A sufficiently far to position the stylus 49 of the pickup arm 46 over the initial playing groove of a 10-inch record. However, as has been explained before, if the uppermost record on the turntable is a 12-inch record it will engage the lever 51 and stop the movement

of the pickup arm so that the stylus 49 is positioned over its initial playing groove. The spring tension, which forces the lever 61 to move in a clockwise direction (Fig. 6) also forces the record-gripping arms to their normal non-gripping position to be described hereafter.

As the pickup arm 46 is being moved from its outermost position to a position over the initial playing groove of a record, the eccentric portion 68B of the cam wheel 57 is in engagement with the pin 63. As this eccentric portion moves, it gradually lowers the pickup arm 46. At the time the stylus 49 of the pickup arm 46 is over the initial playing groove of a top record on the turntable, the portion 68C moves in the path of the roller 67 permitting the lever 64 and the pin 63 to lower the stylus 49 of the pickup arm 46 into engagement with the initial playing groove and to permit the lever 50 and the pin 51 to return to the full-line position shown in Fig. 7.

Record-moving mechanism

The record-moving mechanism is best illustrated in Figs. 1-6, 8 and 11 and includes a pair of brackets 69-69 fixed to and extending above the base plate 14. The brackets 69-69 are provided with a pair of pins 70-70 which pivotally support a supporting member 71. Fixed to the member 71 is a segmental gear 72. As will be described hereafter, the segmental gear 72 is adapted to rotate the member 71 around the common axis of the pins 70-70.

Housing 73 is connected to the member 71 by a locking nut 74 in such a manner that the housing 73 may rotate around its longitudinal axis and relative to the member 71. The housing 73 is adapted to be held in two stable positions relative to the member 71. This is accomplished by a spring-biased ball 75 which is adapted to engage the notches 76 and 77 at different times. When the housing 73 is in the position shown in Fig. 4, the spring-biased ball 75 is in engagement with the notch 76. When the housing 73 is rotated 180° about its longitudinal axis relative to the member 71 from the position shown in Fig. 4, the spring-biased ball 75 comes into engagement with the notch 77. At one end of the housing 73 there is affixed thereto a short shaft 78 which supports a pinion gear 79. As will be described hereafter the pinion gear 79 is adapted to cooperate in rotating the housing 73 about its axis and the axis of the shaft 78.

A pair of arms 80 and 81 are pivotally connected to the other end of the housing 73 by a suitable member 82. Record-gripping portions 80A and 81A are formed on the free ends of the arms 80 and 81 and are provided with grooves 80B and 81B shown in Fig. 8. The grooves 80B and 81B are adapted to engage diametrically opposite peripheral edge portions of the uppermost record supported on the turntable 20. A pair of spring-biased members 83 and 84 are pivotally connected to the arms 80 and 81 as illustrated in Fig. 1. When the arms 80 and 81 are in the position shown in Fig. 1, the spring-biased member 83 rests on top of the arm 80 and the spring-biased member 84 is in engagement with the bottom of the arm 81. After the arms 80 and 81 are rotated 180° about the longitudinal axis of the housing 73 from the position shown in Fig. 1, the relationships between the spring-biased members 83 and 84 and the arms 80 and 81 respectively are reversed. The spring-biased member 83 is in engagement with the under side of the arm 80 and the spring-biased member 84

rests on top of the arm 81. When the arms 80 and 81 are in the positions shown in Fig. 1 and they are moved to gripping position with the uppermost record on the turntable in a manner to be described hereafter, the spring-biased member 83 is adapted to slide over the top of the record to adjust the grooves 80B and 81B into gripping elevation with the top record on the turntable. During this movement of the arms 80 and 81 the spring-biased member 84 engages the periphery of the top record on the turntable and is pivoted relative to the arm 81 against the tension of its biasing spring. When the arms 80 and 81 are rotated 180° about the longitudinal axis of the housing 73 from the position shown in Fig. 1 and thereafter are moved to record gripping position, the spring-biased member 84 moves over the top record on the turntable to adjust the grooves 80B and 81B into gripping elevation with the top record on the turntable. Thus, it is seen that the spring-biased members 83 and 84 are adapted to regulate the elevation of the arms 80 and 81 relative to the top record on the turntable 20 so that the grooves 80B and 81B grip the top record on the turntable when the arms 80 and 81 are moved into gripping position regardless of whether the records on the turntable are of abnormal or normal thickness.

The opposite ends of the arms 80 and 81 are provided with toothed portions 85 and 86 respectively which engage a small gear or rotatable member 87 in the manner shown in Figs. 1 and 4. The gear 87 is provided with a pin 88 which extends radially outward from the peripheral wall thereof and whose function will be described hereafter. The gear 87 is also provided with an extended hub portion the opposite ends of which are provided with notches or driving connections 89 and 90. The gear 87 is rotatably associated with the housing 73 as shown in Fig. 4 and cannot rotate without a force being applied thereto.

A lug 91 provided on a pivotal member 92 is adapted to operatively engage at different times, the notches 89 and 90 to rotate the gear 87 relative to the housing 73. When the gear 87 is in the position shown in Fig. 4, the lug 91 is adapted to operatively engage the notch 89. When the housing 73 is rotated 180° about its longitudinal axis from the position shown in Fig. 4 moving therewith the gear 87, the lug 91 is adapted to operatively engage the notch 90. The member 92 is pivotally supported by a bracket 93 which is connected in a suitable manner to the bottom of the base plate 14 as shown in Fig. 6. The member 92 is maintained in the position shown in Figs. 4 and 6 by a spring 94 connected to the bottom of the base plate 14 and the member 92. The opposite end of the member 92 is swivelly connected to one end of a member 95 by a connecting link 96. Intermediate its ends the member 95 is pivotally connected in a suitable manner to the base plate 14. The opposite end of the pivotal member 95 is connected to a member 97 of a spring-biased coupling member or compression member 98. The compression member 98 also includes a tubular member 99 one end of which is connected in a suitable manner to the member 97 and the other end is connected to a pin 100. The pin 100 is provided with a collar 100A which is adapted to slide within the housing 99. A compression-coil spring 101 is provided in the tubular housing 99, one end abutting the end of the member 97 and the opposite end being engaged by the collar 100A. The opposite end of the pin 100 is connected to

the free end of the lever 61 previously described. When the lever 61 is moved in a counterclockwise direction (Fig. 6) as has been previously explained, the members 95 and 92 are pivoted against the tension of the spring 94 in a corresponding direction. The counterclockwise movement (Fig. 6) of the member 92 while the lug 91 is in engagement with one of the notches 89 or 90 rotates the gear 87 and moves the arms 80 and 81 into record-gripping position previously described. After the arms 80 and 81 are moved to record-reversing or record-discarding position (to be described hereafter) and back to the position shown in Figs. 3 and 4, the cam portion 56A (Fig. 6) moves into the path of the pin 55. This permits the tension of the spring 94 to move the members 92, 95 and 61 to the positions shown in Fig. 6. If the lug 91 is in engagement with one of the notches 89 or 90 while the member 92 is moved in a clockwise direction back to the position shown in Fig. 6, the gear 87 is rotated to move the arms 80 and 81 out of record-engaging position.

As is evident from the description of the mechanism which moves the arms 80 and 81 into and out of record-engaging position, this mechanism is adapted to move the arms 80 and 81 into gripping relationship with disc records of different diameters. For example, let it be assumed that the members 61, 98, 95, 92 and 87 are moved to rotate the arms 80 and 81 into gripping engagement with a 10-inch record. Obviously this assembly of levers and cam 56 are designed to provide sufficient rotary motion to effect such a gripping engagement. On the other hand, when members 61, 98, 95, 92 and 87 are moved to rotate the arms 80 and 81 into gripping engagement with a 12-inch record, less motion is necessary by reason of the larger diameter of the record. Spring 101 in member 98 provides lost motion, thereby allowing lever 61 to continue its normal movement after arms 80 and 81 engage the record without transmitting further motion to levers 92, 95 and 98.

After the arms 80 and 81 have gripped the top record on the turntable, they are then moved upwardly to either of two positions—a record-reversing position shown in dotted lines in Fig. 3 or a record-discarding position from where the arms 80 and 81 may deposit the record carried from the turntable 20 into a magazine 102. The magazine 102 is fixed to the base plate 14 as shown in Figs. 1 and 3.

The magazine 102 includes a back plate 103 and a pair of pins 104—104. As shown in Fig. 3, the pins 104—104 are covered with a suitable cushioning material and are adapted to support a stack of records by engaging their peripheral walls. The pins 104—104 are positioned on the back plate 103 in such a manner that when the arms 80 and 81 are moved to the magazine to deposit a record therein, the pins 104—104 extend between the lower peripheral edge of the gripped record and the inner edges of the arms 80 and 81. The magazine 102 is also provided with wall portions 105—105 to guide the upper peripheral edge portions of a record as it is being deposited into the magazine 102. Below the pins 104—104 there are affixed to the magazine 102 a pair of pins or actuating members 106 and 107 as shown in Fig. 3. When the arms 80 and 81 are moved toward the magazine 102 to deposit a record therein, the pin 88 on the gear 87, previously described, engages one of the pins 106 or 107 and is moved thereby to rotate the gear 87 in a clockwise direction (Fig. 1) to move the arms 80 and 81 into non-gripping

positions. When the housing 73 and the gear 87 are in the position shown in Fig. 1 and are moved to the magazine 102 from this position, the member 88 will engage the pin 106. When the housing 73 is rotated 180° about its axis from the position shown in Fig. 1 and thereafter is raised toward the magazine 102, the member 88 engages the pin 107. The engagement of the member 88 by one of the pins 106 or 107 rotates the gear 87 in a clockwise direction (Fig. 1) to move the arms 80 and 81 out of record-engaging position to permit the record held thereby to be deposited into the magazine 102. With the housing 73 in record-discarding position, the pinion 78 on the shaft 78 is out of the path of a segmental gear 127 (Fig. 4) which will be described hereafter. Since the segmental gear 127 does not operatively engage the pinion 78 during a record-discarding cycle, the housing 73 is not rotated about its longitudinal axis during the record-discarding cycle.

The movement of the arms 80 and 81 from the full-line position shown in Fig. 3 to record-reversing position or record-discarding position previously referred to is performed by a mechanism which includes the segmental gear 72 previously mentioned and which is fixed to the member 71. The segmental gear 72 is positioned to be engaged by another segmental gear 109 which is pivotally mounted on a pin 110 which is supported by the bracket 16. The gear portion of the segmental gear 109 has a mutilated portion 109A as shown in Fig. 2 which permits the free movement of the segmental gear 72 when either of the spring-biased members 83 or 84 move over the top record on the turntable to adjust the elevation of the arms 80 and 81 as previously described. The segmental gear 109 is also provided with a pin 109B. When the gear is moved in a counterclockwise direction (Fig. 2) to move the arms 80 and 81 to record-discarding position (to be described hereafter), the pin 109B will engage the member 85, associated with the turntable elevating mechanism, to move it in the manner previously described.

45 The segmental gear 109 is swivelly connected to one end of a beam 111. Intermediate the ends of the beam 111 there is provided a pin 111A. The opposite end of the beam 111 is provided with a bifurcated portion as shown in Fig. 2 which serves as a sliding connection between the beam 111 and the shaft 58. The shaft 58 has fixed thereto a cam wheel 112 to rotate therewith. The pin 111A is adapted to be guided by cam groove areas 113—117 in the face of the cam wheel 112 to move the beam 111 over different paths. The beam 111 is moved over one of these paths when the pin 111A is guided by the cam groove areas 113, 114, 116 and 115 and it is guided over a different path when the pin 111A is guided by the cam groove areas 113, 114, 17 and 115.

50 A member 118 is pivotally connected to the face of the cam wheel 112 in the common area of grooves 117, 114 and 116. As will be described presently, the member 118 is adapted to be maintained in the dotted-line position shown in Fig. 2 by a mechanism to be described presently. The member 118 is provided with an extension pin 118A which extends through a slot 119 provided in the cam wheel 112. A lever 120 is pivotally connected intermediate its ends to a suitable bracket 121 fixed to the bottom of the base plate 14. One end of the lever 120 is adapted to be moved into and out of the path of the pin 118A. The opposite end of the lever 120 is swivelly connected by a pin 122 to a lever 123. The opposite

end of the lever 120 is connected, in a suitable manner not shown in the drawings, to a manually controlled lever 124. The free end of the lever 124 has a knob 125 which extends up through a slot 126 in the base plate 14 and is adapted to be moved to two positions marked on the base plate (Fig. 1)—the one-side position and the both-sides position. When the knob 125 is moved to the both-sides position, it moves the lever 120 out of the path of the pin 118A as shown by the full-line position illustrated in Fig. 11. When the knob 125 is moved to the one-side position, the lever 120 is moved into the path of the pin 118A as shown by the dotted-line position in Fig. 11. As will be evident from the description hereafter, when the lever 120 is in the path of the pin 118A, the member 118 is maintained in the dotted-line position shown in Fig. 2 and the pin 111A is guided into the cam groove portion 114 during each revolution of the cam wheel 112. Thus, while the lever 120 is in the path of the pin 118A, during each successive record-changing cycle the arms 80 and 81 are moved to record-discarding position.

The rotation of the shaft 58 is initiated by a suitable tripping mechanism as previously stated. The rotation of the cam wheels 112 and 51 is so timed that after the pickup arm 46 has moved to its outermost position the cam groove portion 114 moves into engagement with the pin 111A. Thereafter, the continued rotation of the cam wheel 112 moves the beam 111 to pivot the segmental gear 109 in a counterclockwise direction (Fig. 2). This counterclockwise movement of the segmental gear 109 rotates the segmental gear 72 in a clockwise direction (Fig. 2) and rotates the member 71 about the axis of the pins 70—70 in a clockwise direction (Fig. 1). The clockwise movement of the member 71 raises the housing 73 and therewith the arms 80 and 81 to move the top record from the turntable 20. When the member 118 is in the full-line position shown in Fig. 2, the portion 118B thereof comes into engagement with the pin 111A and guides it into the cam groove portion 116. When the heel portion 118C of the member 118 comes into engagement with the pin 111A, the member 118 is rotated to the dotted-line position shown in Fig. 2. When the pin 111A moves from the cam groove portion 114 to the cam groove portion 115 by the path of the cam groove 116, the movement of the beam 111 is limited in such a manner as to raise the arms 80 and 81 to the record-reversing position shown by dotted lines in Fig. 3. When the cam groove portion 115 comes into engagement with the pin 111A, it moves the beam 111 to pivot the segmental gear 109 in a clockwise direction (Fig. 2). The clockwise movement of the segmental gear 109 moves the segmental gear 72, the member 71 and the housing 73 in such a manner as to lower the arms 80 and 81 to place the record gripped thereby back on the turntable.

On the next revolution of the cam wheel 112, the arms 80 and 81 are again raised when the pin 111A is guided by the cam groove portion 114. However, at the beginning of this revolution of the cam wheel 112, the member 118 is in the dotted-line position shown in Fig. 1. When the member 118 is in this position the pin 111A is not obstructed by the portion 118B and is guided from the groove 114 to the groove 117. Since on this revolution of the cam wheel 112 the cam groove portion 114 guides the pin 111A over its full length, the beam 111 is moved farther to the right (Fig. 2) than it was moved dur-

ing the last revolution of the cam wheel 112 and the arms 80 and 81 are moved correspondingly farther from the turntable. When the pin 111A engages the portion 118D, it pivots the member 118 from the dotted-line position shown in Fig. 2 to the full-line position shown in Fig. 2. While the pin 111A is being guided by the cam groove portion 117 to the cam groove portion 115, the pin 83 is actuated either by the pin 106 or 107 to actuate the arms 80 and 81 to disengage the record gripped thereby and deposit it into the magazine 102. After the record that is gripped by arms 80 and 81 is deposited into the magazine 102, the cam groove portion 115 comes into engagement with the pin 111A and begins to move the beam 111 to the left (Fig. 2) and to rotate the segmental gear 109 in a clockwise direction (Fig. 2). The clockwise movement of the segmental gear 109 lowers the arms 80 and 81 back to the position shown in Figs. 1 and 3. In this position the arms 80 and 81 are at the same elevation as the top record on the turntable.

If, before rotating the cam wheel 112 through another cycle, the lever 120 is moved into the path of the pin 118A (Figs. 2 and 11), it is evident that at the beginning of the rotation of the cam wheel 112 the pin 118A would move into engagement with the lever 120 and move the member 118 from the full-line to the dotted-line position shown in Fig. 2. As is clear from the description above, by this setting of the member 118 on the cam wheel 112 the arms 80 and 81 are again moved to record-discarding position.

When the housing 73 and the arms 80 and 81 are elevated to record-reversing position previously described, they are rotated 180° about the longitudinal axis of the housing 73 by a mechanism shown in Figs. 4 and 5 and which includes the pinion 79. With the pinion 79 in record-reversing position shown in dotted-lines in Fig. 3, it is adapted to be rotated 180° about the axis of the shaft 78 by a mechanism which includes a segmental gear 127 rotatably fixed to a shaft 128 which is mounted on a bracket 129 fixed to the bottom of the base plate 14. The shaft 128 also has fixed rotatably thereto a gear 130. The gear 130 is adapted to be driven by a worm gear 131 provided on one end of a shaft 132 which is rotatably mounted intermediate its ends to the bracket 129. The opposite end of the shaft 132 has a worm gear 133 which is adapted to be driven by a gear 134 rotatably fixed to the driving shaft 58. During a record-changing cycle, after the gear 79 assumes the dotted-line position shown in Fig. 3, the segmental gear 127 is moved into driving engagement therewith by the rotation of the shaft 58. The rotation of the gear 79 by the segmental gear 127 rotates the housing 73 and the arms 80 and 81 180° about the longitudinal axis of the housing 73 and completely turns over the record gripped by the arms 80 and 81 so that when the record is again lowered onto the turntable its opposite side is exposed for reproduction.

The mode of operation

The general mode of operation will now be described. In this mode of operation it will be assumed that the knob 125 is moved to the both-sides position shown in Fig. 1. First, a stack of records is placed in centered position on the turntable 20 and the turntable is manually lowered to the proper position by turning the indicator head 40 to the number on the dial 41 corresponding to the number of records placed on the turntable 20.

After the top record on the turntable is reproduced and the stylus 49 of the pickup arm 46 moves into the tripping groove of the record, a tripping mechanism (not shown) is initiated to start the rotation of the shaft 58. The rotation of the cam wheels 57 and 112 with the shaft 58 is so timed that the first operation which occurs after the shaft 58 begins to rotate is to lift the stylus 49 of the pickup arm 46 out of engagement with the top record on the turntable 20. This operation is brought about by the cam portion 68A of the cam wheel 57 moving into engagement with the roller 67 on the lever 64 to raise the lever 64 and the pin 63 from the position shown in Fig. 7. The upward movement of the pin 63 raises its collar 63A to raise the ear 60 on the lever 54 into the notch 62 of the lever 61. The upward movement of the pin 63 also pivots the lever 50 in a counterclockwise direction (Fig. 7) into engagement with the bottom of the pickup arm 46. Thereafter the continued upward movement of the pin 63 raises the pickup arm 46 and therewith the stylus 49 out of engagement with the top record on the turntable.

After the pickup arm 46 is raised, the cam portion 56C of the cam wheel 57 engages the pin 55 and moves it and therewith the lever 54 to the right (Fig. 6). The counterclockwise movement of the lever 54 moves the lever 61 in a corresponding direction. It also moves the tubular shaft 47 and the pickup arm 46 until the pickup arm is in its outermost position. The counterclockwise movement of the lever 61 moves the members 85, 92 and the gear 87 in a counterclockwise direction (Figs. 4 and 6). The counterclockwise movement of the gear 87 moves the arms 80 and 81 into engagement with the top record on the turntable.

The next operation of the record-changing mechanism is to raise the arms 80 and 81 into record-reversing position. This is brought about by the cam wheel 112 which, by means of the cam groove portion 114, guides the pin 111A to move the beam 111 to the right from the position shown in Fig. 2. The movement of the beam 111, which is being guided by the cam groove 114, rotates the segmental gears 109 and 72 to move the member 71, the housing 73 and the arms 80 and 81 to record-reversing position (dotted-line position shown in Fig. 3).

After the arms 80 and 81 have been raised to record-reversing position, the segmental gear 127 engages and moves the pinion gear 79 to rotate the housing 73 relative to the member 71 180° about its longitudinal axis. This rotary movement of the housing 73 moves the arms 80 and 81 to reverse the record gripped thereby. During the reversal of the record gripped by the arms 80 and 81, pin 111A is guided by the cam groove 116. While the pin 111A is being guided by the cam groove 116 it engages the portion 118C of the member 118 to move the member 118 from the full-line to the dotted-line position shown in Fig. 2. As a result of this setting of the member 118, during the succeeding record-changing cycle, the pin 111A will be guided by the cam grooves 113, 114, 117 and 115 to raise the arms 80 and 81 to record-discard position.

After the record gripped by the arms 80 and 81 is reversed, the pin 111A is guided by the cam groove 115 to move the beam 111 back to the position shown in Fig. 2. This movement of the beam 111 rotates the segmental gears 109 and 72 to lower the housing 73 from the dotted-line po-

sition to the full-line position shown in Fig. 3. By this lowering movement of the housing 73, the record engaged by the arms 80 and 81 is lowered back onto the turntable 20.

Thereafter, the cam portion 56A of the cam wheel 57 moves into the path of the pin 55. This permits the tension of the spring 94 to move the levers 92, 61 and 54 in a clockwise direction (Fig. 6). The clockwise movement of the lever 92 moves therewith the gear 87 to move the arms 80 and 81 out of gripping relationship with the top record on the turntable. The clockwise movement of the lever 54 moves the shaft 47 and the pickup arm 46 in a corresponding direction. The clockwise movement of the pickup arm 46 moves it from its outermost position to a position where the stylus thereof is over the initial playing groove of the top record on the turntable.

While the stylus 49 of the pickup arm 46 is being moved over on the initial playing groove of a record on the turntable, the eccentric cam portion 68B of the cam wheel 57 moves into engagement with the roller 67 to permit the lever 64 and the pin 63 to move back to the position shown in Fig. 7. The downward movement of the pin 63 permits the lever 50 to rotate under the biasing action of the spring 52 in a clockwise direction from the dotted-line position to the full-line position shown in Fig. 7. The downward movement of the pin 63 also permits the stylus 49 of the pickup arm 46 to move into engagement with the initial playing groove of the top record on the turntable. Thereafter, the rotation of the shaft 58 is stopped and the reverse side of the top record on the turntable is reproduced.

After the reverse side of the top record on the turntable is reproduced and the stylus 49 of the pickup arm 46 moves into the tripping groove, the tripping mechanism (not shown) is initiated again to start the rotation of the shaft 58 and therewith the cam wheels 57 and 112.

The first operation which occurs during this revolution of the shaft 58 is the lifting of the stylus 49 of the pickup arm 46 out of engagement with the top record on the turntable 20. This operation is brought about in a manner already described.

Thereafter the pickup arm 46 is swung to an outermost position in a manner also previously described. During the outward movement of the pickup arm 46, the arms 80 and 81 are brought into gripping engagement with the top record on the turntable in a manner also previously described.

After the pickup arm 46 is in its outermost position and the arms 80 and 81 are in gripping engagement with the top record on the turntable, the cam portion 114 comes into engagement with the pin 111A. During this cycle of record-changing operation since the member 118 is in the dotted-line position (Fig. 2) the full length of the cam groove 114 guides the pin 111A. This permits the movement of the beam 111 far enough to the right (Fig. 2) to rotate the segmental gears 109 and 72 sufficiently to move the housing 73 and the arms 80 and 81 to record-discard position.

As the segmental gear 109 is being rotated to move the housing 73 and the arms 80 and 81 to record-discard position, the element 109B engages the member 35 and moves it sufficiently to raise the turntable 20 a distance corresponding to the thickness of one record. Also, while the housing 73 is being moved to record-discard position, the member 38 comes into engage-

ment with either the member 106 or the member 107 and is moved thereby to move the arms 80 and 81 out of record-gripping engagement with the record carried thereby. This permits the record to be deposited into the magazine 102. While the arms 80 and 81 are in record-discarding position, the pin 111A is guided by the cam groove 117 and during this time, no movement is transmitted to the beam 111. While the pin 111A is being guided by the cam groove 117, it comes into engagement with the portion 118D of the member 118 to move it to the full-line position shown in Fig. 2. With the member 118 in this position during the next cycle of rotation of the shaft 58, the pin 111A is guided for a record-reversing operation.

After the cam groove 115 comes into engagement with the pin 111A, the cam groove 115 guides the pin 111A to move the beam 111 back to the position shown in Fig. 2, thereby moving the arms 80 and 81 back to the full-line position shown in Fig. 3.

Thereafter, the pickup arm 46 is swung inwardly from its outermost position to move the stylus 49 over the initial playing groove of the top record on the turntable. Then the pickup arm and the stylus is lowered into engagement with the record.

The next and following cycles of automatic operation are initiated by an automatic tripping mechanism (not shown) which is actuated each time the stylus 49 moves into a tripping groove of a record.

While there has been described what is at present considered the preferred embodiment of the invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. In an automatic phonograph having a rotatable turntable for supporting a stack of records of different diameters, means for moving said turntable vertically relative to its axis for maintaining the top record thereon at a predetermined elevation, and a pickup arm for reproducing the top record on said turntable; the combination of pickup arm-moving means for moving said pickup arm to an outwardmost position and returning it to the initial playing groove of the top record on said turntable; record-moving means mounted beyond the periphery of said turntable for moving to a record-reversing position; record-reversing means connected to said record-moving means for moving therewith and for moving relative thereto when said record-moving means is in the record-reversing position for reversing the top record; a pair of arms connected to said record-reversing means for moving relative thereto into engagement with the top record on said turntable and for moving therewith to the record-reversing position, said arms normally being in a position beyond the periphery of the top record on said turntable and at the predetermined elevation of the top record; a rotatable member operatively connected to said arms for cooperating in moving said arms into and out of engagement with the top record; means for connecting said rotatable member with said pickup arm-moving means, said connecting means including a compressible member for ab-

sorbing the force transmitted from said pickup arm-moving means after said arms are in engagement with the top record; and driving means operatively associated with said pickup arm-moving means, said record-moving means and said record-reversing means and being actuated when one side of the top record on said turntable is played for respectively moving said pickup arm to the outermost position, moving said arms into engagement with the top record, moving the top record to the record-reversing position, reversing the top record, returning the reversed record to said turntable, returning said pickup arm to the initial playing groove of the reversed record, and moving said arms out of engagement with the reversed record.

2. In an automatic phonograph having a rotatable turntable for supporting a stack of records and a record magazine; the combination of means for moving said turntable vertically relative to its axis for maintaining the top record thereon at a predetermined elevation; record-moving means mounted beyond the periphery of said turntable for moving to a record-discarding position; a pair of arms connected to said record-moving means for moving relative thereto into engagement with the top record on said turntable and for moving therewith to the record-discarding position, said arms normally being in a position beyond the periphery of the top record on said turntable and at the predetermined elevation of the top record; a rotatable member on said record-moving means and operatively associated with said arms for cooperating in moving said arms into and out of engagement with the top record; and an actuating member on said record magazine for moving said rotatable member as said record-moving means is moved to the record-discarding position; said turntable-moving means, said record-moving means and said rotatable member being actuated when the top record on said turntable is played for respectively moving said arms into engagement with the top record, moving the top record to the record-discarding position, depositing the top record into said magazine, moving said turntable to move the top record thereon to said predetermined elevation, and returning said arms to the normal position.

3. In an automatic phonograph having a rotatable turntable for supporting a stack of records, and a record magazine; the combination of means for moving said turntable vertically relative to its axis for maintaining the top record thereon at a predetermined elevation; record-moving means mounted beyond the periphery of said turntable for moving to a record-discarding position; a pair of arms connected to said record-moving means for moving relative thereto into engagement with the top record on said turntable and for moving therewith to the record-discarding position, said arms normally being in a position beyond the periphery of the top record on said turntable and at the predetermined elevation of the top record; a rotatable member on said record-moving means and operatively associated with said arms for cooperating in moving said arms into and out of engagement with the top record; an actuating member on said record magazine for moving said rotatable member as said record-moving means is moved to the record-discarding position; and driving means operatively associated with said turntable-moving means, said record-moving means and said rotatable member and being actuated after the

playing of the top record on said turntable for respectively moving said arms into engagement with the top record, moving the top record to the record-discarding position, depositing the top record into said magazine, moving said turntable to move the top record thereon to the predetermined elevation, and returning said arms to the normal position.

4. In an automatic phonograph having a rotatable turntable for supporting a stack of records, a pickup arm for reproducing the top record on said turntable, and a record magazine; the combination of means for moving said turntable vertically relative to its axis for maintaining the top record thereon at a predetermined elevation; pickup arm-moving means for moving said pickup arm to an outermost position and returning it to the initial playing groove of the top record on said turntable; record-moving means mounted beyond the periphery of said turntable for moving to a record-discarding position; a pair of arms connected to said record-moving means for moving relative thereto into engagement with the top record on said turntable and for moving therewith to the record-discarding position, said arms normally being in a position beyond the periphery of the top record on said turntable and at the predetermined elevation of the top record; a rotatable member on said record-moving means and operatively associated with said arms and said pickup arm-moving means for cooperating in moving said arms into and out of engagement with the top record; an actuating member on said record magazine for moving said rotatable member as said record-moving means is moved to the record-discarding position; and driving means operatively associated with said turntable-moving means, said record-moving means and said pickup arm-moving means and being actuated after the playing of the top record on said turntable for respectively moving said arms into engagement with the top record, moving the top record to the record-discarding position, depositing the top record into said magazine, moving said turntable to move the top record thereon to the predetermined elevation, returning said arms to the normal position, and returning said pickup arm to the initial playing groove of the top record on said turntable.

5. In an automatic phonograph having a rotatable turntable for supporting a stack of records of different diameters, a pickup arm for reproducing the top record on said turntable, and a record magazine; the combination of means for moving said turntable vertically relative to its axis for maintaining the top record thereon at a predetermined elevation; pickup arm-moving means for moving said pickup arm to an outermost position and returning it to the initial playing groove of the top record on said turntable; record-moving means mounted beyond the periphery of said turntable for moving to a record-discarding position; a pair of arms connected to said record-moving means for moving relative thereto into engagement with the top record on said turntable and for moving therewith to the record-discarding position, said arms normally being in a position beyond the periphery of the top record on said turntable and at the predetermined elevation of the top record; a rotatable member on said record-moving means and operatively associated with said arms for cooperating in moving them into and out of engagement with the top record on said turntable; means for connecting said rotatable member with said pickup

arm-moving means, said connecting means including a compressible member for absorbing the force transmitted by said pickup arm-moving means after said arms are in engagement with the top record on said turntable; an actuating member on said record magazine for moving said rotatable member as said record-moving means is moved to the record-discarding position; and driving means operatively associated with said turntable-moving means, said record-moving means and said pickup arm-moving means and being actuated after the playing of the top record on said turntable for respectively moving said arms into engagement with the top record on said turntable, moving the top record into the record-discarding position, depositing the moved record into said magazine, moving said turntable to move the top record thereon to the predetermined elevation, returning said arms to the normal position, and returning said pickup arm to the initial playing groove of the top record on said turntable.

6. In an automatic phonograph having a rotatable turntable for supporting a stack of records, and a record magazine; the combination of means for moving said turntable vertically relative to its axis for maintaining the top record thereon at a predetermined elevation; record-moving means mounted beyond the periphery of said turntable for moving to record-reversing and record-discarding positions; record-reversing means connected to said record-moving means for moving therewith and for moving relative thereto when said record-moving means is in the record-reversing position for reversing a record; a pair of arms connected to said record-reversing means for moving relative thereto into engagement with the top record on said turntable and for moving therewith to said record-reversing and record-discarding positions, said arms normally being in a position beyond the periphery of the top record on said turntable and at the predetermined elevation of the top record; a rotatable member operatively associated with said arms for cooperating in moving said arms into and out of engagement with the top record on said turntable and being associated with said record-reversing means for moving therewith; and actuating means on said magazine for moving said rotatable member as said record-moving means is moved to the record-discarding position; said record-moving means, said record-reversing means and said rotatable member being adapted to be actuated for respectively moving said arms into engagement with the top record on said turntable, moving the top record to the record-reversing position, reversing the moved record, returning the reversed record to said turntable, and moving said arms out of engagement with the reversed record; said turntable-moving means, said record-moving means and said rotatable member thereafter being actuated for respectively moving said arms into engagement with the reversed record, moving the reversed record to the record-discarding position, depositing the reversed record into said magazine, moving said turntable to move the top record thereon to the predetermined elevation, and returning said arms to the normal position.

7. In an automatic phonograph having a rotatable turntable for supporting a stack of records, and a record magazine; the combination of means for moving said turntable vertically relative to its axis for maintaining the top

record thereon at a predetermined elevation; record-moving means mounted beyond the periphery of said turntable for moving to record-reversing and record-discardng positions; record-reversing means connected to said record-moving means for moving therewith and for moving relative thereto when said record-moving means is in the record-reversing position for reversing a record; a pair of arms connected to said record-reversing means for moving relative thereto into engagement with the top record on said turntable and for moving therewith to said record-reversing and record-discardng positions, said arms normally being in a position beyond the periphery of the top record on said turntable and at the predetermined elevation of the top record; a rotatable member operatively associated with said arms for cooperating in moving said arms into and out of engagement with the top record on said turntable and being associated with said record-reversing means for moving therewith; actuating means on said magazine for moving said rotatable member as said record-moving means is moved to the record-discardng position; and driving means associated with said record-moving means, said record-reversing means and said rotatable member for respectively moving said arms into engagement with the top record on said turntable, moving the top record on said turntable to the record-reversing position, reversing the moved record, returning the reversed record to said turntable, and moving said arms out of engagement with the reversed record; said driving means thereafter being adapted to be actuated for respectively moving said arms into engagement with the reversed record, for moving the reversed record to the record-discardng position, depositing the reversed record into said magazine, moving said turntable to move the top record thereon to the predetermined elevation, and returning said arms to the normal position.

8. In an automatic phonograph having a rotatable turntable for supporting a stack of records, a pickup arm for reproducing the top record on said turntable, and a record magazine; the combination of means for moving said turntable vertically relative to its axis for maintaining the top record thereon at a predetermined elevation; pickup arm-moving means for moving said pickup arm to an outermost position and returning it to the initial playing groove of the top record on said turntable; record-moving means mounted beyond the periphery of said turntable for moving to record-reversing and record-discardng positions; record-reversing means connected to said record-moving means for moving therewith and for moving relative thereto when said record-moving means is in the record-reversing position for reversing a record; a pair of arms connected to said record-reversing means for moving relative thereto into engagement with the top record on said turntable and for moving therewith to the record-reversing and record-discardng positions, said arms normally being in a position beyond the periphery of the top record on said turntable and at the predetermined elevation of the top record; means for operatively connecting said arms with said pickup arm-moving means and including a rotatable member associated with said record-reversing means for moving therewith; and actuating means on said magazine for moving said rotatable member as said record-moving

means is moved to the record-discardng position; said record-moving means, said record-reversing means and said pickup arm-moving means being adapted to be actuated for respectively moving said arms into engagement with the top record on said turntable, moving said record to the record-reversing position, reversing the moved record, returning the reversed record to said turntable, and moving said arms out of engagement with the reversed record; said turntable-moving means, said record-moving means and said pickup arm-moving means thereafter being adapted to be actuated for respectively moving said arms into engagement with the reversed record, moving said reversed record to the record-discardng position, depositing the reversed record in said magazine, moving said turntable to move the top record thereon to the predetermined elevation, and returning said arms to the normal position.

9. In an automatic phonograph having a rotatable turntable for supporting a stack of records of different diameters, a pickup arm for reproducing the top record on said turntable, and a record magazine; the combination of means for moving said turntable vertically relative to its axis for maintaining the top record thereon at a predetermined elevation; pickup arm-moving means for moving said pickup arm to an outermost position and returning it to an initial playing groove of the top record on said turntable; record-moving means mounted beyond the periphery of said turntable for moving to record-reversing and record-discardng positions; record-reversing means connected to said record-moving means for moving therewith and for moving relative thereto when said record-moving means is in the record-reversing position for reversing a record; a pair of arms connected to said record-reversing means for moving relative thereto into engagement with the top record on said turntable and for moving therewith to the record-reversing and record-discardng positions, said arms normally being in a position beyond the periphery of the top record on said turntable and at the predetermined elevation of the top record; a rotatable member operatively associated with said arms for cooperating in moving said arms into and out of engagement with the top record on said turntable and being associated with said record-reversing means for moving therewith; means for connecting said rotatable member with said pickup arm-moving means, said connecting means including a compressible member for absorbing the force transmitted by said pickup arm-moving means after said arms are in engagement with the top record on said turntable; and actuating means on said magazine for moving said rotatable member as said record-moving means is moved to the record-discardng position; said record-moving means, said record-reversing means, and said pickup arm-moving means being actuated for respectively moving said arms into engagement with the top record on said turntable, moving the top record on said turntable to the record-reversing position, reversing the moved record, returning the reversed record to said turntable, and moving said arms out of gripping engagement with the reversed record; said turntable-moving means, said record-moving means, and said pickup arm-moving means thereafter being actuated for respectively moving said arms into engagement with the reversed record, moving the reversed record into the record-discardng position,

depositing the reversed record in said magazine, moving said turntable to move the top record thereon to the predetermined elevation, and returning said arms to the normal position.

10. An automatic phonograph comprising a rotatable turntable and a record-moving mechanism including a support pivotally mounted on a horizontal axis adjacent said turntable, a pair of record-gripping arms pivoted together beyond the periphery of said turntable for movement towards and away from each other, pivotal means connecting said support and said arms for providing rotation of the arms about an axis 90° displaced with respect to said horizontal axis, rotatable means including oppositely projecting connections operatively associated with said record-gripping arms for moving them towards and away from each other and into and out of engagement respectively with a record on said turntable, driving means disposed adjacent said turntable to engage one of said connections, means operatively associated with said support for moving said support and said arms about said horizontal axis and means operatively associated with said pivotal means for rotating it through an angle of 180°.

11. An automatic phonograph comprising a rotatable turntable and a record-moving mechanism including a support pivotally mounted on a horizontal axis adjacent said turntable, a pair of record-gripping arms pivoted together beyond the periphery of said turntable for movement towards and away from each other and mounted

5 on said support, a rotatable member operatively associated with said arms on said support for moving them into or out of engagement with a record on said turntable, means for driving said rotatable member and means operatively associated with said support for tilting it with respect to said turntable.

10 12. An automatic phonograph comprising a rotatable turntable, a record-receiving magazine adjacent said turntable and a record-moving mechanism including a support pivotally mounted on a horizontal axis between said turntable and said magazine, a pair of record-gripping arms pivoted together beyond the periphery of said turntable for movement towards and away from each other, pivotal means connecting said support and said arms for providing rotation of the arms about an axis 90° displaced with respect to said horizontal axis, means operatively associated with said record-gripping arms for moving them towards and away from each other and into or out of engagement respectively with a record on said turntable, means operatively associated with said support for moving said support and said record-gripping arms about said horizontal axis between the turntable and the magazine, means operatively associated with said pivotal means for rotating said arms about said displaced axis and means on said magazine for engaging and operating said arm moving means when said arms are adjacent said magazine.

JERALD D. WEAVER.
